[57] **CLAIM**

The ornamental design for a box-type wrench for ovularly-shaped valve handles, as shown and described.

DESCRIPTION

FIG. 1 is a top view of the box-type wrench for ovularly-shaped valve handles according to this invention with a handle insert shown in broken lines for purposes of illustration.

FIG. 2 is a right side view thereof.

FIG. 3 is a left side view thereof.

FIG. 4 is a bottom view thereof.

FIG. 5 is a front view thereof.

FIG. 6 is a back view thereof.

FIG. 7 is a sectional view taken at 7—7 in FIG. 1 for illustration purposes only to show the hole relation shapes.

FIG. 1

FIG. 2

FIG. 3

FIG. 4

FIG. 5

FIG. 6

FIG. 7
